UNITED STATES PATENT OFFICE.

CHARLES L. BASTIAN, OF CHICAGO, ILLINOIS.

HAND-OPERATED FIRE-EXTINGUISHER.

1,342,580.

Specification of Letters Patent. Patented June 8, 1920.

Application filed January 8, 1916. Serial No. 70,971.

To all whom it may concern:

Be it known that I, CHARLES L. BASTIAN, a citizen of the United States, residing at Chicago, in the county of Cook and State 5 of Illinois, have invented certain new and useful Improvements in Hand-Operated Fire-Extinguishers, of which the following is a specification.

This invention relates to a hand-operated 10 fire extinguisher and has for its principal object the provision of a compact and easily operated means adapted to contain a supply of liquid and to eject the liquid in the form of a stream which may be directed as 15 desired.

A further object of my invention is the provision in a fire extinguisher of operating means therefor which allows a stream of liquid to be directed at will without interfering with the ease with which the device is 20 operated.

Another object of my invention is the provision of a hand-operated fire extinguisher having its outlet normally closed by a valve 25 which is automatically and instantaneously released when the operating means is actuated.

A still further object of my invention is the provision of a hand-operated fire extinguisher comprising a minimum number 30 of simple and relatively inexpensive parts none of which are liable to be injured by careless use or continued neglect or disuse of the device.

Further objects and advantages of my invention will be apparent as it is better understood by reference to the following specification when read in connection with the accompanying drawing, illustrating the preferred embodiment thereof, in which—

Figure 1 is a vertical section through the mechanism according to my invention;

Fig. 2 is a vertical section through the mechanism in a plane normal to the plane 45 of Fig. 1;

Fig. 3 is a detail in elevation of the operating crank and the locking means therefor, and

Fig. 4 is a detail in elevation of the locking means for the crank illustrating the inoperative position thereof.

Referring to the drawing, 1 indicates a casing, which is preferably cylindrical and closed at either end by the end members 2 and 3. Supported within the casing 1 is a threaded rod 4, one end of which is disposed

in a suitable bearing 5 formed integrally with the end member 2, the other end projecting into a hollow bearing member 6 secured to the end member 3. The end 7 of 60 the rod 4 within the bearing member 6 is reduced in size to allow the passage of liquid from the interior of the casing 1 through an opening 6' to a nozzle 8 from which the liquid is ejected in the form of a 65 stream and is provided with a conical end 7' adapted to engage the valve seat 9 to prevent the passage of liquid into the nozzle 8 under conditions presently to be explained. Journaled on the bearing member 6 is a 70 bevel pinion 10 which is supported by a plate 11 secured to the end member 3, balls 12 being disposed between the pinion 10 and the plate 11 to reduce the friction therebetween. A pin 9' on the rod 4 engages a 75 slot 10' in the pinion 10 and provides an operative connection therebetween. Rotatably mounted in the end member 3 is a shaft 13 having a bevel gear 14, preferably formed integrally therewith and meshing 80 with the pinion 10. A manually operable crank 15, having a handle 16, is secured to the shaft 13 and serves to rotate the shaft 13. A gland 17 prevents the liquid within the casing 1 from escaping about the 85 shaft 13.

A plunger 18 threadedly engages the rod 4 and is provided with an asbestos packing ring 19 held in position by a ring 20 threadedly engaging a flange 21 of the plunger 90 18; and a washer 22, also preferably of asbestos, is held in position by a resilient member 23 which is clamped to the plunger 18 by a threaded collar 25. A gland 25 surrounding the rod 4 prevents the escape of 95 liquid from the interior of the casing 1. Surrounding the bearing 5 is a spring 27 which engages the plunger 18 when at the limit of its travel in the direction of the end member 2 and forces the rod 4 upwardly, viewing Figs. 1 and 2, so that the conical end 7' thereof engages the valve seat 9 to prevent escape of liquid from the interior of the casing 1 to the nozzle 8.

The end of the crank 15 is notched at 28 105 (Fig. 3) and is adapted to be engaged by a spring-pressed latch 29, slidably mounted in a casing 30 secured to the exterior of the casing 1. The spring 31 normally forces the latch 29 outwardly and owing to the 110 configuration of the end of the crank 15 it may be rotated in one direction but is pre-

vented from rotation in the reverse direction. The latch 29 is provided with a handle 32 operating in an L-shaped slot 33, in the casing 30, and when the handle 32 is disposed in the position indicated in Fig. 4 the latch 29 is withdrawn from position to engage the end of the crank 15. A threaded plug 34 in the end member 3 allows access to the interior of the casing 1 so that it may be readily filled with liquid.

It will be noted from an inspection of Figs. 1 and 2 of the drawings that the rod 4 is slightly shorter than the distance between the end of the bearing 5 and the valve seat 9 so that longitudinal movement of the rod 4 is possible. When the casing 1 is to be filled with liquid the latch 29 is moved to the position indicated in Fig. 4 and the crank 15 is rotated in an anti-clockwise direction to rotate the rod 4 and move the plunger 18 to the limit of its travel toward the end member 2. The spring 27 will be engaged by the plunger 18 and tensioned with the result that the conical end 7' of the rod 4 will be forced into engagement with the valve seat 9 closing the outlet from the casing 1. The latch 29 is then moved to the position indicated in Figs. 1 and 3. This is the normal position of the parts and after the casing 1 has been filled with liquid the device is ready for use. When it is desired to eject the fluid from the casing 1 the crank 15 is rotated in a clockwise direction which is possible without disturbing the latch 29 with the result that the plunger 18 moves upwardly, viewing Figs. 1 and 2. As soon as the tension of the spring 27 has been released the pressure of the fluid within the casing 1 will force the rod 4 downwardly, viewing Figs. 1 and 2, freeing the conical end 7' thereof from the valve seat 9 and the fluid will thereupon issue from the nozzle 8. Upon continued actuation of the crank 15 the plunger 18 will continue to move upwardly until it has forced all of the liquid from the casing 1.

It will be readily understood from the foregoing that the normally closed outlet from the casing 1 is automatically and instantaneously opened by merely rotating the crank 15 and that no knowledge of the device other than that the crank must be actuated is necessary in order that the device may be utilized for its intended purpose. The provision of the latch 29 prevents rotation of the crank in an anti-clockwise direction and hence an excited individual attempting to use the device can not operate it except in the proper manner to eject the liquid from the casing. The device is extremely simple in construction and can not readily be destroyed by careless use nor does it deteriorate with continued neglect or disuse. It is, accordingly, when properly filled with liquid, always ready for imme-

diate use whenever an emergency arises. The provision of a crank for operating the plunger allows the nozzle of the device to be directed as desired without interfering in any manner with the operation since the casing may be readily held in and directed with one hand while the other is employed in operating the crank.

It will be apparent that various changes may be made in the form, construction and arrangement of the parts without departing from the spirit and scope of the invention, or sacrificing any of its material advantages, the form hereinbefore described being merely a preferred embodiment thereof.

I claim:

1. In a fire extinguisher, the combination of a casing adapted to contain a liquid, an outlet from said casing, means for ejecting the liquid from said casing including a longitudinally movable threaded rod and a plunger threadedly engaging said rod, means for rotating said rod, means on said rod to close said outlet, and means at the end of said casing opposite said outlet for engaging said plunger when at the limit of its travel in one direction, moving said rod longitudinally of its axis to close said outlet.

2. In a fire extinguisher, the combination of a casing adapted to contain a liquid, an outlet from said casing, means for ejecting the liquid from said casing including a longitudinally movable threaded rod and a plunger threadedly engaging said rod, means for rotating said rod, means on said rod to close said outlet, and a spring at the end of said casing opposite said outlet for engaging said plunger when at the limit of its travel in one direction, moving said rod longitudinally of its axis to close said outlet.

3. In a fire extinguisher, the combination of a casing adapted to contain liquid, an outlet from said casing, means for ejecting the liquid from said casing including a longitudinally movable threaded rod and a plunger threadedly engaging said rod, means located exteriorly of said casing for rotating said rod including a manually operable member, an operating connection between said member and rod, means on said rod to close said outlet, and resilient means at the end of said casing opposite said outlet engaging said plunger when at its limit of travel in one direction to move said rod longitudinally of its axis and thereby close said outlet.

4. In a fire extinguisher, the combination of a casing adapted to contain a liquid, an outlet from said casing, means for ejecting the liquid from said casing including a longitudinally movable threaded rod and a plunger threadedly engaging said rod, means for rotating said rod including a manually operable crank, a shaft support-

ing said crank and gearing between said shaft and rod, means on said rod to close said outlet, and a spring at the end of said casing opposite said outlet engaging said plunger when at its limit of travel in one direction to move said rod longitudinally of its axis and thereby close said outlet.

5. In a fire extinguisher, the combination of a casing adapted to contain a liquid, an outlet from said casing, means for ejecting the liquid from said casing including a longitudinally movable threaded rod and a plunger threadedly engaging said rod, means for rotating said rod including a manually

operable crank, a shaft supporting said 15 crank, a bevel gear on said shaft, and a bevel pinion operatively connected to said rod and meshing with said bevel gear, means on said rod to close said outlet, and means at the end of said casing opposite said outlet for 20 engaging said plunger when at the limit of its travel in one direction to cause said rod to be moved longitudinally of its axis and thereby close said outlet.

CHARLES L. BASTIAN.
